UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

CONNECTING DEVICE

Application filed February 18, 1929. Serial No. 349,723.

My invention relates to the art of connecting wires particularly electric conductors such as trolley wires and connecting to such wires separably formed bodies as, for instance, terminal members.

The object of my invention is to provide primarily a connector for conductors which shall be simple and strong and maintain the adjacent ends of the wires in a fixed relation. 10 Another object of my invention is to connect the wires without removing from the wires any of the metal thereof so as to reduce the cross section but to have an interlocked relation between the wires and their connector. 15

Another object of my invention is to provide splicers which can be used with trolley wires and maintain the exposed contact surface of the connected wires in alignment and 20 maintain them in a fixed relative relation.

My invention resides in the new and novel construction, combination and relation of the various parts herein described and shown in the accompanying drawing.

25 In the drawing:—

Fig. 1 is a side view of my invention.

Fig. 2 is an end view.

Fig. 3 is an enlarged section on the line 3—3 of Fig. 1.

30 Fig. 4 is a longitudinal view of the lower surface of one form of my splicer shown in Fig. 1 for a limited length thereof.

Fig. 5 is a view showing the splicer in position between the jaws of a means for locking 35 the splicer securely to wires and further shows a plurality of interlocking means between the splicer and wires and two of such means before interlocking and two after interlocking.

40 Fig. 6 is a sectional view on the line 3—3 of Fig. 1 but with a trolley wire in position and mounted between the jaws of a compressing means for moving the interlocking pin to its interlocked relation with the trolley wire.

Fig. 7 is an enlarged sectional view on the line 7—7 of Fig. 5 showing an interlock between the conductor, splicer and pin as completed.

50 Fig. 8 is a sectional view corresponding to

that of Fig. 7 but for a conductor having a uniformly circular cross section.

Fig. 9 represents a longitudinal section of the form shown in Fig. 8 taken on the line 9—9 but without the trolley wire and shows 55 enlargements in the channel for the wire.

Fig. 10 is a sectional view of a trolley wire shown in Fig. 5 before and after the wire has been locked in position.

The connecting of conductors, especially 60 trolley wires used in high speed operation of cars, is one of the important problems confronting an operator. In my invention I provide a device which has the objects set forth above and which, while particularly adaptable to the connecting of trolley wires, either 65 round or grooved types, lends itself to the connecting of other forms of conductors or even for rods which may be used for other purposes than electrical conductors.

In one form of the preferred embodiment 70 of my invention I employ a body member 1 which has a groove or channel 2 extending throughout the length on one edge thereof if the device is to be used with a grooved type 75 of trolley wire, or there may be a channel longitudinally of the body member entirely surrounding the conductor if it is of the round type shown in section in Fig. 8. Where a groove is employed as in Fig. 3 for a grooved conductor I provide oppositely disposed and 80 inwardly projecting lips 3 which are seated in the side grooves of the conductor. Transversely mounted in the body member are a plurality of pins 4 formed preferably of steel. 85 Each pin is positioned in a tubular passage 5 and is formed to fit the pin 4 sufficiently snug to retain the pins and body member as a unitary device, which is a matter of extreme 90 convenience to the user of the splicer.

The pin 4 is preferably formed of a solid 95 cylindrical rod having an elongated portion 6, having at the inner end a reduced portion 7 formed with sides 8 which are parallel or substantially parallel to the sides of the portion 6. The portion 7 is adapted to be forced into and interlocked with the trolley conductor 9. The upper or exposed end of the pin 4 has a reduced tapered portion 10 and a still more tapered and pointed portion 11. 100

The body member 1 is formed with an annular flange 12 which is adapted to engage with the tapered portion 10 when the pin has been interlocked with the conductor to prevent a backward or releasing movement of the pin 4. The shoulder 13 may form a means of gauging the depth to which the pin interlocks with the conductor.

In either of the forms shown by section in Figs. 7 and 8, I employ separably formed means for moving the pins into interlocked relation with the conductor 9. The movement imparted to the pin 9 is a movement in line with the axis of the pin and substantially transverse to the axis of the trolley wire. Splicers have been made with screws which have imparted thereto two movements, namely, a rotated movement which, due to the threaded surface, imparts to the screw a movement transverse to the wire. However, with my invention I am able to employ a pin having a relatively small diameter and upon which no twisting movement is applied but only a straight end force, and with sufficient pressure the end of the pin is formed into the trolley wire, displacing a portion of the metal with the end of the pin, and therefore distorting the trolley wire at that point but not reducing the cross section. In order to provide for the distorted condition of the trolley wire, the groove is formed with enlargements or pockets 14 adjacent the point where the pin interlocks with the wire or the passage 5 meets the longitudinal groove 2.

It is quite essential to keep down the thickness or horizontal width of the body member 1 when a device is used as a connector for trolley wires because in many instances a grooved wheel is used and it is advisable for the best operation to offer as little obstruction to the passage of the wheel as possible. With my construction I am able to use a pin of much smaller diameter than the diameter of a screw and at the same time I am able to enter the pin into the conductor at a much greater distance than is possible where a screw is used and forced into the trolley wire through its pointed or cup-shaped end cutting its own interlock with the wire. Such screw ends are usually tapered and tend to force the trolley wire out of engagement with the screw when longitudinal stress is placed upon the wire. In order to interlock a screw with the trolley wire to any satisfactory depth, a very large screw must be used in order to get the proper strength or if a screw of small diameter is used, the trolley wire must be countersunk first by removing metal to form a recess therein. It will be quite evident that if a screw is substituted in Fig. 7 for the pin 4 that as the screw moves into engagement with the trolley wire 9, its tendency will be to force the trolley wire out of the groove.

By employing a press of the design shown in Figs. 5 and 6, or its equivalent, I am able to force the trolley wire and the pin 4 into interlocked engagement by moving the two relatively toward each other, allowing the body 1 to maintain a normal relation with respect to the trolley conductor, that is, there is no tendency for the trolley wire to be pushed out of its normal relation with respect to the groove in the body member.

The press comprises a U-shaped yoke member 30 having a fixed part 31 with a grooved seat 32; a threaded passage 33 and a steadyng handle 34. Mounted in the passage 33 is a screw 35 provided with a squared or other conveniently formed end 36 to which may be applied a ratchet or open end type of wrench or other convenient means for rotating the screw 35. To the lower end of the screw 35 is secured a head 37 which moves transversely with the screw 35 but is mounted with a ball thrust bearing 38, thereby rotating relatively to the screw 35.

The head 37 is provided with a two part recess in its lower face, one of which engages with the centering portion 11 of the pin and which offers also a surface against which pressure is applied by the press.

Assuming the connector and wire to be positioned as shown in Fig. 6, the screw 35 is rotated, moving the head 37 into contact with the pin, thereby forcing it toward the trolley wire as the screw is rotated. When the portion 7 of the pin engages with the trolley wire and further rotation is applied to the screw 35, the end 7 of the pin is forced into the conductor 8, thereby displacing the metal of the wire and forming a recess for the pin and the displaced metal is forced into the enlargements 14.

Just before the pin reaches its final interlocked position, the cup shaped portion of the head 37 engages with the flange 12 and automatically forces the flange inwardly to engage with the tapered portion 10 of the pin as the pin moves forward, thus the interlocking of the pin with the conductor and the interlocking of the pin with the splicer is brought about simultaneously by the same operation.

It will be seen that the force on the pin is applied entirely axial and the only movement necessary to the pin is an axial movement transverse to the axis of the trolley wire, and that the trolley wire is supported against movement relative to the splicer. The same is true with either of the forms shown in Figs. 7 and 8. The body member 1 is usually made of a non-ferrous alloy or metal but it can be made of a ferrous metal if so desired.

It will be recognized that my invention when applied to trolley conductors of the type shown in Fig. 7, that I have formed a connection between the connected wires which will maintain them in a fixed relative

position with a smooth, straight, uninterrupted, exposed surface and in which the trolley wire will not move out of interlocked relation with the pins, due to the end 7 of the 5 pins having substantially straight and parallel sides.

I claim:

1. A wire splicer comprising an elongated body member, an open edge groove along one edge of the body to receive wires from both ends and inwardly projecting means to prevent the wires being displaced transversely of the groove and a plurality of means slidably mounted in the body member and movable transversely of the axis of the wires to interlock with the wires to prevent its moving longitudinally in the groove.

2. A wire splicer comprising an elongated body member, a groove to receive wires from both ends and means to prevent the wires being displaced transversely of the groove and a plurality of means slidably mounted in the body member and movable transversely of the axis of the wires to interlock with the 25 wires below the surface thereof to prevent them moving longitudinally in the groove.

3. A wire splice comprising an elongated body member, wire receiving means, a pair of longitudinally aligned wires having depressions below the wire surface and a plurality of means slidably mounted in the body member and movable transversely of the axis of the wire to interlock with the wire depressions to prevent its moving longitudinally in 35 the passage.

4. A wire splicer comprising an elongated body member, wire receiving means for the wires to be spliced, a plurality of slidably mounted holding means movable transversely 40 of the wire axis to interlock with the wires to prevent longitudinal movement and bent-over means to prevent movement of the holding means to release the wires.

5. A wire splicer comprising an elongated body member, an open slot along an edge of the body to receive wires, a plurality of slidably mounted pins mounted in passages having axes transverse to and opening into the wire receiving axes and having ends adapted 45 to enter pockets formed in the wire and opening at the surface.

6. A wire splicer comprising an elongated body member, receiving means for wires, a plurality of passages having axes transverse 55 to the wire receiving means and pins slidably movable in the passages and having ends with substantially parallel sides to project at one end into the wire receiving means and means on the body to engage the other end 60 of the pin to prevent movement in the opposite direction.

7. A wire splicer comprising a body member, receiving means for wires, a plurality of tubular passages opening into the receiving 65 passage, the receiving passage having sepa-

rately formed and oppositely disposed enlargements adjacent the openings of the tubular passages and positioned on opposite sides of the axes of the tubular passages and means mounted in the tubular passages to be moved into interlocking engagement with the wires and force the displaced metal of the wires into the enlargements.

8. A wire splicer comprising a body member, an open slot along an edge of the body to receive wires, a plurality of tubular passages opening into the receiving passage, the receiving passage having oppositely inwardly projecting means to retain the wires against transverse displacement and enlargements adjacent the openings of the tubular passages on opposite sides of the axis of the tubular passages, and means mounted in the tubular passages to be moved into interlocking engagement with the wires and force the displaced metal of the wires into the enlargements and means to hold the movable means in locked position with the wires.

9. A wire splicer comprising an elongated body member having an open groove along one edge with inwardly projecting and oppositely disposed lips to engage grooves in wires positioned in the open groove, a plurality of tubular passages opening into the open groove, the grooves having enlargements mounted in the tubular passages to be moved into interlocking engagement with the wires and force the displaced metal of the wires into the enlargements and means to hold the pins in locked position with the wires.

10. A wire splicer comprising a body member to receive the wires to be spliced with a portion of the longitudinal surface exposed and pins movable in a transverse direction only to the axis of the wires to interlock with the surface of the wires opposite the exposed surface.

11. A wire splicer comprising a body member to receive the wires to be spliced and pins movable in a transverse direction only to the axis of the wires to interlock with the wires and means on the pins to be engaged with means on the body member simultaneously with the movement of the pins to lock the pins in engagement with the wires.

12. The combination of a wire, a body positioned on the wire by a relative longitudinal movement and held against relative transverse movement and a pin slidable in the body with a single movement towards the side face of the wire to enter the wire for a limited distance thereof and form its own recess in the wire, the pin having a reduced end with substantially parallel sides to take the longitudinal strain off the wire at substantially right angles to the sides of the reduced pin end.

13. The method of connecting wires comprising positioning on the wires with abut-

ting ends, a body member, then slidably moving pins having blunt ends and mounted in the body towards the wires, and forcing the ends of the pins into the wires and displacing metal of the wires and locking the wires and body against relative movement.

14. The method of connecting wires comprising positioning on the wires with abutting ends a body member, having slidably mounted pins therein, applying a force to one end of the pins and a counter force to the conductor to move and force the other end of the pins into the wires and lock the wires and body against relative movement.

15. In testimony whereof I affix my signature.

SAMUEL S. MATTHES.
